UNITED STATES PATENT OFFICE.

HAROLD J. MEYER, OF ST. JOSEPH, MISSOURI.

DISPENSING AND DISPLAY DEVICE.

1,402,635.

Specification of Letters Patent.

Patented Jan. 3, 1922.

Application filed May 12, 1921. Serial No. 468,958.

To all whom it may concern:

Be it known that I, HAROLD J. MEYER, a citizen of the United States, residing at St. Joseph, in the county of Buchanan and State 5 of Missouri, have invented certain new and useful Improvements in Dispensing and Display Devices, of which the following is a specification, reference being had therein to the accompanying drawing.

10 My invention relates to improvements in that class of easels, which detachably hold and display a number of articles which are removed from the easel as they are sold, or for other purposes, and the objects of my improvements are first: To so construct an easel 15 of this class, that the display board of the easel shall detachably hold a number of paper bags, containing goods and which board shall not be marred or injured in any way 20 by securing said bags thereon or by removing them therefrom; thereby providing an easel which can be used continually, by replenishing said bags of goods, and securing them on the display board after the first ones 25 are sold and removed therefrom, second; to so construct and proportion the display board that said bags can easily and quickly be secured thereon and removed therefrom and on which board there is ample room for 30 the application thereon of appropriate matter which is descriptive of the contents of the bags, etc., third, to provide foldable supporting means, by which said display board is substantially supported in an inclined position when in use and can be folded, to occupy the minimum amount of space, for 35 storage and shipment.

I attain these objects by the devices illustrated in the accompanying drawings, in 40 which:

Figure 1 is a front view of the easel and of a number of bags detachably secured thereon. Fig. 2 is a side view of the easel. Fig. 3 is a rear view of the supporting means, in 45 detail, folded flat against the display board. Fig. 4 is a top view of the parts seen in Fig. 2, looking downward toward the left, showing the inclined braces in position for use. Fig. 5 is a fragmentary side view of a portion of the easel, showing the bag holding 50 means in detail.

The easel comprises the display board 1, through which the incisions 2 are made. Said board is preferably formed of substantial 55 cardboard. The upper end portions of the bags 3, are folded flat and are inserted

through said incisions, as seen in Fig. 5. The reenforcing piece 4, the legs 5 and the braces 6, which are provided with the notches 7 formed in their respective edges 60 are formed preferably of one piece of cardboard, as seen in Fig. 3.

The incisions 8 are formed through said legs, for the reception of the notched ends of said braces.

Said reenforcing piece is glued or otherwise secured on the back of the display board 1. The braces and the legs are bent on their respective dotted lines 9 and 10, are moved from the position seen in Fig. 3 to the position seen in Fig. 4, and the ends of said braces are passed through the incisions 8, until the notches 7 are moved into engagement with said legs, at the lower ends of said incisions, by the elastic movement of 75 said braces. It will be seen that the lower ends of said incisions are on the level with the upper ends of said notches, (in Fig. 3,) and that the end portions of said braces are forced upward, before inserting them into 80 said incisions, thereby causing their above described movement.

It will be seen in Fig. 5, that the edges of the display board 1, which bound the longitudinal edges of the incisions 2, are forced 85 into the position shown, when the upper end portion of the bag 3 is passed therethrough. Said edges of said board elastically press against said portion of said bag, thereby clamping the latter between them for de- 90 tachably holding said bag in place.

It will also be seen in Figs. 2 and 4, and understood, that the braces 6 detachably hold the legs 5 against lateral movement.

In removing the bag 3, from the display 95 board 1, said bag is lifted from the position shown and its upper end portion is thereby drawn from the incision 2. The ends of the braces 6 are lifted and their notches disengaged from the legs 5, after which said legs 100 and braces are folded against the display board 1, when they are not in use.

Having fully described my invention, what I claim as new and desire to secure by Letters Patent, is:

1. A display board provided with a plurality of horizontally disposed incisions formed therethrough, the portions of said display board which form the longitudinal boundaries of said incisions forming clamping means whereby the upper end portions of folded paper bags may be clamped for de- 110

tachably holding said bags in place, on said display board.

2. A dispensing easel comprising; a display board for detachably holding a plurality of paper bags thereon; a reenforcing piece secured on the back of said display board; a pair of legs formed integrally with said reenforcing piece for supporting said display board in an inclined position, each

10 one of said legs being provided with an in-

cision formed therethrough; and a brace for each one of said legs said braces being cut from the same blank forming the reenforcing piece and legs and provided with notches formed therein for engagement with said legs respectively at the lower ends of said incisions, for detachably holding said legs against lateral movement.

In testimony whereof I affix my signature.

HAROLD J. MEYER.
